United States Patent

Des. 236,882
Patented Sept. 23, 1975

236,882

COMBINED CLOCK AND TIMER

Paul T. Flumm, Oakville, Conn., assignor to
Robertshaw Controls Company

Filed Aug. 20, 1973, Ser. No. 390,039

Term of patent 14 years

Int. Cl. D10—03

U.S. Cl. D10—40

FIG.1

FIG.2

FIG.3

FIG.4

FIG. 1 is a front elevational view of a combined clock and timer showing my new design;

FIG. 2 is a left elevational view thereof;

FIG. 3 is a right side elevational view thereof;

FIG. 4 is a rear elevational view thereof.

The spring shown in FIGS. 2 and 4 is shown partially broken away for convenience of illustration.

I claim:

The ornamental design of a combined clock and timer, substantially as shown and described.
